UNITED STATES PATENT OFFICE

JOHN C. AGAR, OF CHICAGO, ILLINOIS, ASSIGNOR TO SWIFT AND COMPANY, OF CHICAGO, ILLINOIS, A CORPORATION OF ILLINOIS

CARCASS-CHILLING SUPPORT

Application filed June 28, 1929. Serial No. 374,346.

This invention relates to packing house methods and means, such as are conducive to the most desirable conditioning of carcass parts; especial reference being had to maintaining a pleasing and approximately natural form and position for the flanks on sides of beef and the like while the sides are being chilled and set pursuant to dressing.

The main objects of the invention are to provide an improved form of flank support adapted for use on a chilling rack or table; to provide such a support of adjustable construction for horizontal expansion and contraction according to the kind or size of flank to be supported; to provide a sectional block style of support having a plurality of spaced parallel connecting screws and common operating means therefor to facilitate manual control adjustment; to provide depending means for cooperating the adjusting screws; and to provide in combination with such a support a corresponding rack or table apertured to accommodate such depending means and so enable ready adjustment thereof from below.

An illustrative embodiment of this invention is shown by the accompanying drawings in which:

Figure 1 is a vertical section on the line 1—1 of Fig. 2.

Fig. 2 is a plan of a beef chilling table provided with a flank supporting filler block of adjustable character.

Fig. 3 is a vertical section on the line 3—3 of Fig. 2.

Fig. 4 is an enlarged side view of the filler block.

Fig. 5 is an end view of said block.

Fig. 6 is a bottom plan view of the block.

Fig. 7 is a vertical section on the line 7—7 of Fig. 4.

Fig. 8 is a plan showing a filler block and the middle part of a chilling table representing a modification of Fig. 2.

Fig. 9 is a vertical section on the line 9—9 of Fig. 8.

Referring first to Figs. 1, 2 and 3, the filler block 1 rests on the chilling rack or table 2 whereon a side of beef 3, or other carcass, indicated in dotted outline, is laid bone side

down with the flank part resting on the block 1. These devices constitute part of the chilling room equipment.

In order to provide somewhat for adjustment of said block according to the size and shape of the flank to be supported, it is made in two relatively movable sections 4 and 5 disposed side by side and normally fitting snugly together, as indicated at 6.

Further details of the filler block are best shown by Figures 4 to 7. Here, as will be seen, the two sections 4 and 5, disposed side by side, are connected by a pair of parallel screws 7 adapted and arranged for controlling the expansion of the block by relative movement of its sections. The said screws 7 are provided with coturnable sprocket wheels 8 in coplanar alinement, said wheels being connected by a chain 9 for coactuation, as will be described. Each block section is recessed to receive threaded screw receiving plates 7'. The block as a whole is chambered at 1' to accommodate the wheels 8 and chain 9. These screws are preferably threaded at both ends, the pitch being reversed at 70 opposite ends.

The rack 2 comprises mainly a pair of mutually spaced side bars 12 in combination with a series of spaced cross bars or slats 13, legs 14 and a back rail 15. In order to accommodate the desired position and operation of the filler block 1, which is oblong in shape, with its sections extending lengthwise, one of the frame slats 16 is medially resected and the inner ends of the sections thereof are supported by short longitudinal bars 17 which are secured to the adjacent slats 13, as indicated at 19. This construction provides a longitudinal slot 20 through which the operating chain 9 depends for underneath operation by hand to expand and contract the filler block.

In order to definitely fix the position of the filler block as a whole, as at times may be desirable, dowel pins 21 may to advantage be set in one of the sections, as for instance, in section 5, appropriate sockets or holes being provided in the slats 13 to receive said pins when the block is set in place. These pins may be threaded at one end for ready removal or replacement. See Fig. 7. 100

Referring to Figures 8 and 9, a simplified form of rack is here shown, the construction being the same as in Fig. 2 except that instead of providing a longitudinal slot for the chain 9, the latter is passed around one of the slats 13. Here, in order to install the block, or remove the same, one of the chain links has to be unjointed, as will be understood, on account of its passing around slat 13 instead of merely depending through a slot, such as shown at 20 on Figure 2.

In using this device, a carcass side is laid upon the rack 2 with the inner face of the flank resting upon the block 1. The attendant then observes the fit of the block relative to the flank and this is perfected by pulling the chain 9 one way or the other, and the block so opened or closed more or less, until the desired fit is obtained, so that the flank will be held in its natural or most preferred position during the chilling period.

Although but two specific embodiments of this invention are herein shown and described, it is to be understood that some details of the constructions shown may be altered or omitted without departing from the spirit of this invention as defined by the following claims.

I claim:

1. As a packing house accessory, a flank support comprising a pair of complementary members correlated for mutual adjustment horizontally.
2. As a packing house accessory, a flank support comprising a pair of complementary members correlated for mutual adjustment horizontally and having manually operable depending means adapted and arranged for effecting change of adjustment from below.
3. As a packing house accessory, a flank support comprising a pair of complementary block members disposed side by side, sprocket screw means connecting said members and a depending chain adapted and arranged for manual operation of said means from below.
4. As a flank support an adjustably expandable filler block comprising a pair of complementary parts formed appropriately with respect to the flanks to be supported, in combination with a part of mutually spaced parallel screws adapted and arranged to effect expansion and contraction of said support, said screws having sprocket wheels in coplanar alignment thereon and a chain in engagement therewith for manual operation of said screws.
5. An adjustable two-section flank support having a pair of parallel screws to control the mutual spacing of said sections and means to operate and coordinate the action of said screws, said sections having threaded bearings set therein to receive said screws and the latter each being oppositely threaded at their ends.
6. A carcass side holder comprising an apertured planar member to receive the meat,

bone side down, in combination with an adjustable flank support having depending operative means for adjusting said support from below, the latter being so positioned relative to said holder that the holder aperture will accessibly accommodate said operative means.

Signed at Chicago this 24th day of June, 1929.

JOHN C. AGAR.
